UNITED STATES PATENT OFFICE.

NIELS WALTERSEN AASEN, OF CHRISTIANIA, NORWAY.

HAND-GRENADE WITH TIME-FUSE AND AUTOMATIC RELEASE.

1,275,190.

Specification of Letters Patent. Patented Aug. 13, 1918.

Application filed July 20, 1917. Serial No. 181,728.

To all whom it may concern:

Be it known that I, NIELS WALTERSEN AASEN, a subject of the King of Norway, residing at Christiania, Norway, have invented 5 certain new and useful Improvements in Hand-Grenades with Time-Fuses and Automatic Releases; and I do hereby declare the following to be a full, clear, and exact description of the invention, such as will enable 10 others skilled in the art to which it appertains to make and use the same, reference being had to the accompanying drawings, and to figures of reference marked thereon, which form a part of this specification.

15 The present invention relates to a hand grenade with time fuse and has particularly for its object an improved safety device for a grenade of this type.

A form of the invention is illustrated on 20 the drawing:

Figure 1 is an axial section through the grenade.

Fig. 2 is an end view and

Fig. 3 is a side view of the same.

25 The grenade itself consists of the cylindrical box 1 provided with an axial tube 2, in which the ignition mechanism is placed. The latter is of the friction type, the movable part 3 of which is actuated by a spring 4, 30 which on the drawing is shown in a compressed condition. The spring 4 is pressing against a disk 5, which is supported against one leg of the angular member 13. The friction cord 3 is fastened to two hoops on the 35 disk 5 by means of pin 6.

The ignition mechanism ignites a fuse 7 through which the fire is conducted to the detonator 8 which in turn ignites the explosive charge in the grenade box itself. 40 The detonator 8 may be placed in the tube 2 through the lower open end of the same and is kept in position by means of wood plug 9 and screw cap 10. The explosive charge is introduced in the grenade through the neck 45 11 covered by screw cap 12.

The spring 4 is maintained in a compressed condition by means of the said angular member 13, one leg of which extends across one end of the box over the disk 5, 50 while its other leg lies along the side of the box. The angular member 13 is kept in position by means of a hook or catch 14 gripping one free end of one leg of the angular member 13, while the other leg is held against the side of the box by means of a ribbon 15 wound about the same, and as a further

safety against loosening of the member 13 a bolt 17 with a flat head 18 is introduced through a hole in the long leg of member 13 into a recess 16 in the side of the box. The 60 said bolt may be made hollow as illustrated on the drawing and should then be provided with a weight 19 in order to be easily acted upon by centrifugal force. The ribbon 15 is wound over the flat head 18 of this bolt. 65 The angular member 13 has its lower end bent as shown at 20 in order to grip the lower edge of the box, so that it can not perform an axial movement even if the hook 14 is loosened or broken off.

Covering the ribbon and bolt 17 a plate 21 is mounted on the grenade box by means of four ears 22 and a wire hook 23, the two legs of which fit into the ears 22 protruding through plate 21.

In the above described condition the grenade is packed for transport. In order to use the grenade the safety hook 23 is first taken out, so that the plate 21 is loose, and thereupon the grenade is gripped with the 80 right hand and thrown with the thumb on the covering plate 21. After having passed a number of meters (for instance 8 meters) through the air the ribbon rolls off and the safety bolt 17, 18 slips out of its hole. The 85 angular member 13 is then not longer pressed against the side of the grenade and is swung off pivoting on the hoop 14, the spring 4 pressing disk 5 with friction device upward. The fuse is ignited and the same is so proportioned that after an ordinary throw it ignites the detonator immediately after the 90 grenade has struck the ground. If the grenade is thrown too short, it will however roll along the ground before exploding, 95 which is an advantage for instance in case the grenade should drop a short distance in front of an enemy trench.

The detonator may be transported separately and put in place immediately before 100 the grenades are distributed to the troops, or the detonator may be put in place by the thrower himself.

The grenade above specified besides its simple and cheap production also offers the 105 advantage of greater safety against involuntary explosion than the grenades hitherto in use.

At the same time the security of the explosion is very great, the same being not 110 dependent on the grenade striking hard ground, which is mostly the case in grenades

with percussion fuse. The safety hook 23 is easily removed so that after a little experience a soldier is able to prepare and throw as many as 25 grenades a minute.

5 I claim:

1. In a hand grenade with time fuse a spring actuated friction device for igniting the fuse of the grenade automatically when released, and a ribbon wound about the body of the grenade in such a manner as to keep the spring in a compressed condition, said ribbon being arranged to unwind itself, when the grenade is thrown, thereby releasing said spring.
15. 2. In a hand grenade with time fuse a spring actuated friction device for igniting the fuse of the grenade automatically when released, an angular member the short leg of which lies across one end of the grenade body and acts as a support for the spring of the friction device, the free end of said short leg being gripped by a hook fastened to the grenade body, the other leg of said angular member lying against the side of the grenade box, and a ribbon wound about the grenade body and leg for securing the said angular member in its position on the grenade.
20. 3. In a hand grenade with time fuse a spring actuated friction device for igniting the fuse of the grenade automatically when released, an angular member the short leg of which lies across one end of the grenade body and acts as a support for the spring of the friction device, the free end of said short leg being gripped by a hook fastened to the grenade body, the other leg of said angular member lying against the side of the grenade box, and a ribbon wound about the grenade body and leg for securing the said angular member in its position on the grenade.
25. 35. 4. In a hand grenade with time fuse a spring actuated friction device for igniting the fuse of the grenade automatically when released, an angular member the short leg of which lies across one end of the grenade body and acts as a support for the spring of the friction device, the free end of said short leg being gripped by a hook fastened to the grenade body, the other leg of said angular member lying against the side of the grenade box, and a ribbon wound about the grenade body and leg for securing the said angular member in its position on the grenade, and a bolt with a flat head passing through a hole in said leg of the angular member, and a ribbon wound about the grenade body over said bolt and lock for securing the said angular member in its position on the grenade.

4. In a hand grenade with time fuse a 45 spring actuated friction device for igniting the fuse of the grenade automatically when released, an angular member the short leg of which lies across one end of the grenade body and acts as a support for the spring of the friction device, the free end of said short leg being gripped by a hook fastened to the grenade body, the other leg of said angular member lying against the side of the grenade box, and a ribbon wound about the grenade body and leg for securing the said angular member in its position on the grenade, the leg of the angular member extending along the side of the grenade being bent inwardly at its lower end, so as to grip 50 the edge of the grenade body in order to prevent axial displacement of the angular member even if the hook gripping the other leg of the same should be broken.

5. In a hand grenade with time fuse a 65 spring actuated friction device for igniting the fuse of the grenade automatically when released, an angular member the short leg of which lies across one end of the grenade body and acts as a support for the spring 70 of the friction device, the free end of said short leg being gripped by a hook fastened to the grenade body, the other leg of said angular member lying against the side of the grenade box, and a ribbon wound about 75 the grenade body and leg for securing the said angular member in its position on the grenade, and a covering plate fastened to the side of the grenade body over the ribbon by means of ears of the grenade body and a pin 80 through said ears.

In testimony that I claim the foregoing as my invention, I have signed my name in presence of two subscribing witnesses:

NIELS WALTERSEN AASEN.
